UNITED STATES PATENT OFFICE.

CHARLES M. HEETER AND JOSEPH W. HEETER, OF BUTLER, PENNSYLVANIA.

CONTROL PACKER HEAD.

Application filed December 18, 1924. Serial No. 756,704.

To all whom it may concern:

Be it known that we, CHARLES M. HEETER and JOSEPH W. HEETER, both citizens of the United States, residing, respectively, at Butler, county of Butler, and State of Pennsylvania, have invented a new and useful Improvement in Control Packer Heads, of which the following is a full, clear, and exact description.

The present invention relates broadly to oil well equipment, and more particularly to a packer head by means of which oil flowing from a well can be collected and saved during the setting of the tubing.

At the present time it is customary in the art to which the present invention relates, after a hole has been drilled to the desired depth, to lower into the hole an anchor carrying a packer adapted to be expanded against the walls of the hole. The anchor may be of any desired length, whereby the packer will be supported at the required distance above the bottom of the well. The present invention relates to a device adapted to be secured above the packer for receiving the oil and delivering it around the tubing, whereby it may be recovered by means of a flow catcher, as well understood in the art.

In the accompanying drawings, there is shown for purposes of illustration only, a preferred embodiment of the present invention, it being understood that the drawings do not define the limits of the invention and that changes in the construction therein disclosed may be made without departing from the spirit of the invention or the scope of our broader claims.

In the drawings:

Figure 1 is a side elevation of the packer head, the parts being shown in extended relation;

Figure 2 is a view similar to Figure 1, showing the parts in telescoped relation; and

Figure 3 is a vertical sectional view, illustrating the parts in an intermediate position.

A packer head constructed in accordance with the present invention preferably comprises a sleeve 2 having its lower end threaded to receive a coupling 3, which is in turn

threaded to cooperate with a tube or pipe section 4 which may extend downwardly to or comprise part of a packer of any desired construction.

55

The opposite end of the sleeve 2 is shaped to provide a projecting shoulder or bead 5 adapted to cooperate with a collar 6 which is placed over the sleeve before the coupling 3 is secured in position. The collar 6 has a threaded portion 7 of reduced diameter adapted to receive the lower end of a casing 8 of a diameter such that it may easily slide over the sleeve 2. The upper end of the casing 8 is reduced and provided with a threaded portion 9 adapted to receive a coupling 10 which at its opposite end is threaded onto the flow pipe 11.

60

The upper surface of the coupling 3 is provided with a groove 12 having a packing 12' and the lower end of the collar 6 is provided with a projection 13 adapted to form a tight fit with this groove and packing when the parts are in telescoped position, as indicated in Figure 2.

75

The sleeve 2 is provided with one or more openings 14, preferably of elongated form, adapted to permit any fluid which flows upwardly through the coupling 3 and sleeve, as indicated by the arrow A, to flow outwardly around the sleeve and casing 8, as indicated by the arrows B during the time the anchor, the packer and the packer head with its connected piping are being lowered into the well. During this lowering movement the parts are held in extended relation by means of a frangible rivet or bolt 15. During this time also flow through the casing is prevented by a frangible disk 16 which may be of babbitt, cast iron or other metal suitably positioned within the coupling 10 and completely closing its flow opening. The under side of this disk is provided with a recess or pocket 17 cooperating with the upper end of a breaker rod 18 having a shoulder 19 at its lower end and a projection 20. The shoulder 19 engages the lower end of one of the openings 14 and the projection 20 is riveted or otherwise secured to the sleeve by a frangible connection 21. The side of the rod is formed with an inclined surface 22 adapted to project out-

wardly through the opening 14 in such manner as to be engaged by the collar 6 during the telescoping movement of the parts. This movement will be effective for shearing 5 the connection 21 and pushing the rod 18 inwardly toward the center of the sleeve, whereby the inclined portion 23 of the shoulder 19 will be brought into contact with the bottom of the opening 14 to permit the rod to drop out of the opening and on downwardly through the sleeve, packer and anchor.

During the lowering of the entire assembly into a well, the parts will all move in 15 unison until the anchor reaches the bottom of the well. Thereafter the packer will set, checking the further movement of the parts and resulting in the shearing of the pin 15. The sleeve and casing at this time will commence telescoping, such movement being prevented only by the rod 18 and disk 16. Due to the frangible nature of the disk 16, it will be broken to establish a flow opening through the coupling 10 and the pipe 11. 25 Continued telescoping of the parts will bring the collar 6 into engagement with the lower end of the rod 18, resulting in displacing the same and permitting it to fall to the bottom of the well, as before pointed 30 out. Final movement of the parts will bring the lower end of the collar into sealing relationship with the coupling 3 to prevent any further flow of fluid outwardly through the openings 14, and causing all of 35 the fluid to pass axially through the control packer head into the piping 11.

It will be understood that during the lowering of the parts into the well the oil which flows upwardly around the piping 11 can 40 be recovered by any well known form of flow catcher located at the top of the well.

The advantages of the present invention arise from the provision of a packer head adapted to be lowered into a well with the 45 casing for initially deflecting oil outwardly around the piping and for later cutting off such flow of oil and establishing the desired flow through the piping.

We claim:

50 1. A packer head comprising a sleeve having an axially extending opening and a laterally extending opening, a casing adapted to telescope relatively to said sleeve, means normally holding said casing and sleeve in extended relation, and means preventing flow of fluid axially through said sleeve and casing when they are in extended relation, substantially as described.

60 2. A packer head comprising a sleeve having an axial flow opening and a laterally extending flow opening, a casing telescopically mounted relatively to said sleeve, frangible means normally holding said sleeve and casing in extended relation, and frangible 65 means normally preventing axial flow

through said sleeve and casing, substantially as described.

3. A packer head comprising a sleeve having an axial flow opening and a laterally extending flow opening, a casing telescopically mounted relatively to said sleeve, frangible means normally holding said sleeve and casing in extended relation, frangible means normally preventing axial flow through said sleeve and casing, and means for breaking said last mentioned frangible means upon relative movement between the casing and sleeve, substantially as described.

4. A packer head comprising a sleeve having an axial flow opening and a laterally extending flow opening, a casing telescopically mounted relatively to said sleeve, frangible means normally holding said sleeve and casing in extended relation, frangible means normally preventing axial flow through said sleeve and casing, and means for breaking said last mentioned frangible means upon relative movement between the casing and sleeve, said last mentioned means being moved to inoperative position during telescoping of the parts, substantially as described.

5. A packer head comprising a tubular sleeve having a laterally extending flow opening, a coupling carried by said sleeve at one end and formed with a sealing seat, a casing telescopically movable on said sleeve, means normally holding said casing and tube in extended relation, and means carried by said casing adapted to cooperate with said seat when the parts are in telescoped relation, there being means preventing axial flow through said sleeve and casing when the parts are extended, substantially as described.

6. A packer head comprising a tubular sleeve having a side outlet, a casing adapted to telescope with said sleeve to seal said outlet, and means normally preventing axial flow through said sleeve and casing when the parts are in extended relation, substantially as described.

7. A packer head comprising a tubular sleeve having a side outlet, a casing adapted to telescope with said sleeve to seal said outlet, means normally preventing axial flow through said sleeve and casing when the parts are in extended relation, and frangible means normally holding said sleeve and casing in extended relation, substantially as described.

8. A packer head comprising a sleeve having an axial flow opening and a laterally extending flow opening, a casing telescopically mounted relatively to said sleeve, and frangible means normally holding said sleeve and casing in extended relation and preventing axial flow through the casing, and means for breaking said frangible means upon

relative movement between the casing and sleeve, substantially as described.

9. A packer head comprising a tubular sleeve having a side outlet, a casing adapted to telescope with said sleeve to seal said outlet, and frangible means normally preventing axial flow through said casing when the parts are in extended relation, substantially as described.

10. A packer head comprising a tubular

sleeve having a side outlet, a casing adapted to telescope with said sleeve to seal said outlet, and frangible means normally preventing axial flow through said casing when the parts are in extended relation, substantially as described.

In testimony whereof we have hereunto set our hands.

CHARLES M. HEETER.
JOSEPH W. HEETER.

Certificate of Correction.

It is hereby certified that in Letters Patent No. 1,534,851, granted April 21, 1925, upon the application of Charles M. Heeter and Joseph W. Heeter, of Butler, Pennsylvania, for an improvement in "Control Packer Heads," errors appear in the printed specification requiring correction as follows: Page 2, lines 129 and 130, and page 3, lines 1 and 2, of claim 8 strike out the words and comma "and means for breaking said frangible means upon relative movement between the casing and sleeve,"; page 3, lines 3 to 9, strike out present claim 9 and insert the following as claim 9:

9. A packer head comprising a sleeve having an axial flow opening and a laterally extending flow opening, a case telescopically mounted relatively to said sleeve, frangible means normally holding said sleeve and casing in extended relation and preventing axial flow through the casing, and means for breaking said frangible means upon relative movement between the casing and sleeve, substantially as described.;

and that the said Letters Patent should be read with these corrections therein that the same may conform to the record of the case in the Patent Office.

Signed and sealed this 26th day of May, A. D. 1925.

[SEAL.]

KARL FENNING,
Acting Commissioner of Patents.
